UNITED STATES PATENT OFFICE.

MATTHEW VIERENGEL, OF NEW YORK, N. Y., ASSIGNOR, BY MESNE ASSIGNMENTS, TO THE AUTOPRESS COMPANY, OF NEW YORK, N. Y.

INKING APPARATUS FOR PRINTING-PRESSES.

1,004,606.

Specification of Letters Patent.

Patented Oct. 3, 1911.

Application filed October 24, 1905, Serial No. 284,224. Renewed December 14, 1907. Serial No. 406,485.

To all whom it may concern:

Be it known that I, MATTHEW VIERENGEL, a citizen of the United States, residing at New York, in the borough of Brooklyn, county of Kings, and State of New York, have invented a new and useful Inking Apparatus for Printing-PresSES, of which the following is a specification.

This invention has reference to inking apparatus for printing presses in general, and to improvements in adjusting the form-rollers with respect to the form when new and also after they have shrunk or expanded; it also relates to improvements in adjusting the distributing-rollers to the form-rollers and to each other for the purpose of adapting the vibrating-rollers to make close contact with the form-rollers, and the composition distributing roller with the vibrating rollers; and this invention also has reference to the means for vibrating the distributing rollers of printing presses and to the construction of the bearings for the supply-rollers.

The invention and improvements herein described have particular reference to inking-apparatus for printing presses in which the impressions are made by means of a reciprocating form bed and an oppositely reciprocating oscillating impression cylinder having a movement to and from the plane of the form bed, such as described in my application for Letters Patent, Serial No. 406,484, renewed December 14, 1907, for improvements in printing presses.

One object of my invention is to provide an inking apparatus for such a press wherein certain form and distributing rollers are caused to travel with the impression cylinder but without partaking of its movement to and from the plane of the bed so that the distributed ink will be applied to the form during both of the relative movements between the ink-applying or form rollers and the form although impressions are taken from the form only during the movement in one direction between the form and the impression cylinder.

Another object of the invention is to facilitate the adjustment of the form-rolls to the form; and this part of the invention consists in mounting them in a carriage which is vertically adjustable for the purpose of compensating for the contraction and expansion of the rollers from changes in tem-

perature and other causes, and making a proper contact between the form-rolls and the form.

A further object of the invention is to provide for the adjustment of the distributing rollers with respect to the form-rollers for the purpose of maintaining a proper contact and pressure of the same on the form-rollers and provide for adjusting the same when the form-rollers are new and when they contract or expand; and this part of the invention consists in mounting the distributing rollers in a frame, forming part of the carriage, above the form-rollers, which is hinged to the carriage and provided with means for vertically adjusting the same.

The invention consists in the novel parts, improvements and combinations herein disclosed.

The accompanying drawings which are referred to herein and form a part hereof, illustrate one part of the invention and serve in connection with the description to explain the parts thereof.

Of the drawings:—Figure 1 represents a top plan of an inking apparatus, embodying the improvements that form the subject of this application, applied to a printing press having a reciprocating form-bed and an oscillating and reciprocating cylinder—the illustration showing the press broken through, longitudinally and centrally. Fig. 2 is a side elevation of the same. Fig. 3 is a longitudinal vertical section, taken on a line 'x—x' of Fig. 1. Fig. 4 is an end view of the cylinder and form-bed section of the inking apparatus, drawn on an enlarged scale. Fig. 5 is a side elevation of one end of the same, showing the gearing connections. Fig. 6 represents a side elevation, taken from the left-hand side of the press, of the fountain, and the operating mechanism of the ductor and vibrating rollers. Fig. 7 is an end view of an improved bearing for the supply roller, and Fig. 8 is an edge view of the same. Fig. 9 represents an end view of the screw-threaded block by which the vibrating distributing rollers are operated.

The improvements in inking apparatus for printing presses which form the subject of this application, are represented in connection with the improved printing-press described in my application for Letters Patent above referred to. As some parts of the

printing press described in said application are necessarily shown in the drawings, and referred to in the present specifications, these parts are designated by the same reference characters that are used to indicate them in the said application:—Of these reference characters —B—B'— designate the side members of the frame; —D—D'— the uprights and —E—E— the top plates 10 of said side members.

—H— designates the type or form-bed, —I— the impression cylinder, —J—J— the frames in which slide the cross-heads that carry the boxes of the impression cylinder 15 shaft, —K—K— the cams by which the cylinder is pulled down to contact with the sheet on the form at the beginning of its impression movement, it being understood that the cylinder is normally held above the plane of the form by suitable means, as set forth in my copending application above referred to, —17—18— the levers and —20— the pitman by which the form-bed is reciprocated, —34—34— the bed-racks which engage and oscillate the cylinder by means of the toothed-wheels —73—73— on the cylinder shaft, —43—43— the stationary rack-bars, and —42—42— the pinions on the cylinder-shaft that engage the said stationary 25 rack-bars and reciprocate the cylinder.

The inking apparatus is divided into two parts or sections, viz., a reciprocating section in which are included the form-rolls —275—275—275—, a composition distributing roll and vibrating rolls; and a stationary part or section which comprises the ink fountain and supply roller, a vibrator and a ductor roll. The rollers of the reciprocating section of the inking apparatus are mounted 30 in a carriage supported independently of the impression cylinder carriage and so connected thereto as to cause the said section of inking mechanism to travel with the impression cylinder without partaking of the movement 35 of the impression cylinder toward or from the plane of the form bed. As shown, the carriage of the reciprocating section of the inking apparatus is constructed in two parts —L—M—, the former in accordance with one feature of the invention being provided 40 with slides —278—278— that travel or slide on top of the flanges —36—36— bolted to the side members of the frame, and which is connected at the rear end by means of the 45 links —77—77— with the cross-heads —39—39— that carry the cylinder boxes. The section —L— is hinged to the section —M— at the front thereof. Section —M— consists of side plates —279—279— which 50 have fore and aft flanges —280—280— projecting from their bases which are perforated vertically in line with tapped holes —281—281— in the slides —278—278—. Screws —282—282— are passed down 55 through the perforations in the projections and screwed into the slides —278— and thus connect the carriage with said slides. The side plates are also provided with lugs —283— on their inner sides, which are provided with vertical slotted bearings that support the gudgeons —284— of the form-rolls —275—. At their rear ends the side plates have upward extensions or horns —285—285— to which the links —77—77— are pivoted, to connect the inking apparatus and 60 the cross-heads —39—39— that carry the cylinder boxes. The flanges —280—280— are provided with screw holes —286—286— in which set-screws —287—287— are inserted and screwed down so that their ends 65 bear on the slides —278—278—. These set-screws are used to adjust the inking apparatus, as a whole, vertically. The upper part L of the carriage is also formed with side-plates —288—288— the bases of which 70 are extended forward horizontally to form flanges —289—289— which are provided with bolt holes —290—290—. Bolts —291—291—, secured in said bolt-holes —290—290— are provided with flat circular heads 75 which are inserted between jaws —292—292— at the upper front corners of the side-plates of the lower part or section of the carriage, and secured therein by screw-pins —293—293—. These pivoted bolts form 80 hinges by means of which the upper part of the carriage is hinged to the lower part. By this construction the upper part of the carriage is adapted to swing over from its position on the lower part at the front, and thus expose the form-rolls mounted in the lower part of the carriage. The flanges —289— are also provided with screw-holes 85 in which set-screws —294—294— are inserted and screwed down so that their points 90 bear against the top edges of the side-frames of the lower part of the carriage. By means of the set screws the upper part of the carriage is adjustable vertically, relative to the 95 lower part.

In the upper part —L—, the vibrators —295—295— are mounted, over the form-rolls, but in such a position that they are in contact therewith. These vibrators are mounted on shafts —296— the ends of which 100 are supported in the side-frames and are held against rotation by feathers. The ends of the vibrators on the right-hand end of the carriage are fitted with right and left screw-threaded collars —297—297— which are in engagement with the segmental threads in the concave sides of a block —298— which is supported between the collars on a screw-stud projecting from the side-frame. The 105 opposite ends of the vibrators are provided with toothed wheels —299—299—. Above the vibrators there is a composition roller —300— the shaft of which is journaled in boxes in the upward projections of the side-frames of the part —L—, and the boxes are 110

115 120 125 130 132

vertically adjustable by means of screws — 301 between which they are held. The shaft of the composition roller carries a broad face pinion — 302 — which meshes with both of the toothed-wheels — 299 — 299 — on the vibrators below. This pinion is also in gear with an idle-wheel — 303 — mounted on a transverse shaft — 304 — supported in boxes — 305 — 305 — held in vertically adjustable frames — 306 — 306 — which are inserted between the upright horns — 285 — 285 — of the lower part of the carriage which are secured to the boxes — 305 — 305 — by screws — 307 — 307 — driven through holes in the 15 said projections and screwed to the boxes. The front sides of these frames bear against the vertical edges of the side plates of the upper part of the carriage, whereby the box frames are held securely and firmly in place. 20 The frames are adjustable vertically by means of set-screws — 308 — 308 — which are driven through the boxes and bear against the bottom members of the frames. The heads of the screws — 308 — are reached 25 through holes — 308* — 308* — in the cap-plate of the frame, so that by means of a screw-driver the screws can be made to move the frames down or allow them to be moved up when the lower part of the carriage is 30 adjusted vertically.

The idle-wheel — 303 — is in gear with the gear-wheel — 73 — on the cylinder shaft to the left of the cylinder. By this geared connection, when the cylinder oscillates, motion 35 is transmitted to the composition roller, and through the pinion — 302 — to the vibrators — 295 — 295 —. Furthermore at the same time the vibrators are rotated they are also moved endwise by the engagement of the screw-threaded collars — 297 — 297 — with the threaded block — 298 —, and the vibrations of the respective rollers are reversed by the forward and back motion of the cylinder. By means of the set-screws — 287 — the position 40 of the carriage with respect to the slides — 278 — can be readily adjusted to regulate the position of the form-rolls relatively to the form. Thus, when the form-rolls are new, or they swell or expand, they 45 are adjusted by first loosening the screws — 282 — and then screwing down the set-screws and lifting the carriage thereby until a proper contact is obtained between the form-rolls and the form, and then tightening 50 the screws — 282 — 282 — to hold the carriage fast. But as the form-rolls shrink or contract, the set screws are withdrawn more or less to allow the carriage to move closer to the slides and thereby adjust the 55 form-rolls to the form and compensate for the lessened diameter. The carriage is secured by tightening the screws — 282 — 282 —, as before. The vibrators are adjusted to the form-rolls by means of the set-screws 60 — 294 — 294 —. Thus, to adjust them higher

the nuts on the bolts are loosened and the upper part of the carriage is raised by means of the set-screws, and to lower them as the form-rollers shrink or contract, the set-screws are withdrawn more or less and the nuts on the bolts screwed down against the flanges to hold the upper part — L — steady. The composition roller is adjusted by moving the boxes in which the roller shaft is supported vertically by means of the screws, between which the boxes are held. And when the part — M — of the carriage is moved up or down the frames — 306 — 306 — are adjusted to correspond by means of screws — 308 —.

From the above description it will be seen that the adjustment of the form-rollers to the form and the distributing rollers to the form-rollers and to each other is easily effected without removing any of the parts and, as the form-rollers contract or expand in diameter they can be kept in proper position with respect to the forms, by adjusting the height of the lower part — M — of the carriage.

The stationary part of the inking apparatus is located at the rear end of the frame and, as some of the parts have been referred to in the specification and shown in the drawings in the application for Letters 95 Patent for printing presses, heretofore referred to, these parts will be indicated herein by the same reference characters.

The ink-fountain — 78 — is fastened to the rear end of the frame just below the top. 100 The fountain-roller — 79 — is fitted with a ratchet-wheel on the end of its shaft, and the same shaft outside of the fountain carries an arm — 81 — provided with a pawl — 82 — and has a pin — 83 — near the end 105 opposite the pawl, which is engaged by the pitman — 84 — pivoted to a crank-pin — 85 — on a slide — 86 — held in guides — 87 — on the outer side of a cam — 88 —. By the revolution of the said cam a reciprocating motion is given to the pitman — 84 — which in turn swings the arm — 81 — and causes the pawl — 82 — to engage the teeth of the ratchet-wheel — 80 — and thus rotate, intermittently, the fountain-roller. 110 In the extended side-walls of the fountain, near the arm and between the fountain-roller and the frame of the press, the shaft — 89 — is journaled in suitable bearings. This shaft carries two upright arms — 90 — 115 90 — in the upper ends of which are the bearings for the journals of the shaft of the supply roller — 91 —. The shaft — 89 — carries on its right-hand end a pendent arm — 92 — fitted with a roller — 93 — that bears 120 against the face of the cam — 88 —. This cam is mounted on a shaft — 94 — journaled in bearings in the rear uprights — D² — of the side-frames — B — B' —. The shaft — 94 — also carries on the same side behind 130

- the cam a spur-wheel —95— which is in gear with a pinion —96— on a stub-shaft —97— fixed in the upright —D²— and which carries also a toothed-wheel —98— and a sprocket-wheel —98^a— connected by means of a sprocket-chain —99— with a sprocket-wheel —100— on the driving shaft —S—. The toothed-wheel —98— is in gear with a wheel —101— on the end of the transverse shaft —102— mounted in bearings in the uprights just below the top of the frame. This shaft carries between the side frames a vibrator —103—. The supply-roller —91— carries the ink from the fountain-roller to the vibrator and is swung over by means of the cam —88— acting on the arm —92—. To the top-plate —E— E— and just over the uprights —D²—, brackets —104— are bolted which project rearward on the frame of the press. The ends of these brackets connect with bearings in which a shaft —105— is journaled and on which are mounted loosely, arms —106—, and the ends of these arms are formed into bearings for the shaft —107— of a ductor —108—. To the end of the shaft —107— on the left-hand side of the press the upper end of a fork —109— is pivoted, the lower end being coupled to the shaft —94— and having a roller —110— on a stud that bears against the face of a cam —111— mounted on the shaft —94—. When the press is running and the low part of the cam bears against the roller —110— the ductor —108— drops by gravity to the vibrator —103—, but when the high part of the cam bears against the face of the roller fork lifts the ductor to a horizontal position as shown by Figs. 2 and 3.
- 40 The form or type bed —H— has at its rear end an inking table —112— which when the bed moves backward is carried under the ductor —108—. The timing of the cam —111— is such that when the bed moves forward to make an impression the high part of the cam is in contact with the roller —110— and the fork is thereby caused to hold the ductor arms —106— in a horizontal position above the top of the inking-table so that the ductor-roller is in position to contact with and bear down on the surface of the inking-table —112— as the latter moves back under it; and when the inking-table moves past the ductor on the forward movement of the bed the lower part of the cam —111— lets the roller sink and the fork moves down. Thus, the ductor is allowed to swing down in contact with the vibrator —103— and take ink therefrom; and it remains in that position until the inking-table approaches, on the return or backward movement of the bed, when the high part of the cam comes in contact with the roller, and the cam lifts the fork and the ductor is thereby raised or lifted to its upper position, where it contacts with the surface of the inking-table, as it moves backward and transfers the ink to the surface of the inking-table. As the bed moves forward to make an impression and as the cylinder moves backward the form-rollers —275— pass over the form to the inking-table from which they take a fresh supply of ink and on the reverse movement they also roll over the inking-table and from that to the form, and again apply ink to the latter. Thus, during both movements of the bed and cylinder the form-rollers supply ink to the form, and also take a fresh supply from the inking-table.
- 45 The operation of the vibrator —103— is produced by the following mechanism:— The shaft —102— on which the vibrator is mounted is extended on the left-hand side of the press and a screw-threaded sleeve or worm —317— is mounted thereon and connected therewith by means of a spline —318—. A horizontal bracket —319— is connected with the top-plate —E— of the frame and at its outer end an arm —320— is pivoted to it at one end, the opposite end of the arm being forked and coupled to the end of the shaft —102—. On the stud —320^a— in the projection of the bracket —319— a worm-wheel —321— is mounted horizontally and is in gear with the worm —317—. This wheel is provided with a wrist-pin —322— which is inserted in the end of a pitman —323— which connects with the arm —320—. The shaft —102— receives its motion from the driving shaft —S— through the sprocket-chain —99— running over the sprocket-wheel —100— (on the driving shaft) and the sprocket-wheel —98— mounted on said shaft. The shaft —102— rotates the worm and worm-wheel which, through the pitman vibrates the arm —320— and the latter by its forked connection with the shaft —102— moves the shaft and with it the vibrator —103—.
- 50 My invention in its broader aspects is not limited to the particular construction herein shown nor to any particular construction whereby it has been or may be carried into effect, as many changes may be made in the details of the construction without departing from the main principles of the invention and without sacrificing its chief advantages.
- 55 I claim:—
1. In an inking apparatus for printing presses, a carriage having form-rollers and distributing rollers mounted in suitable bearings therein, slides to which the carriage is fastened, guides connected with the frame of the press on which the slides are supported, a reciprocating form-bed, a reciprocating and oscillating impression-cylinder connected with the carriage so that the cylinder and the carriage are reciprocated

- simultaneously and the form-rollers thereby moved over and in contact with the form and the inking-table during both the impression movement and return movement of the cylinder, an inking-table, and means for applying and spreading ink on the inking-table, substantially as specified.
2. In an inking apparatus for printing presses, a carriage having form-rollers and distributing rollers mounted in suitable bearings therein, slides to which the carriage is fastened, guides connected with the frame of the press on which the slides are supported, a form-bed and reciprocating and oscillating impression-cylinder connected with the carriage so that the form-rollers are moved over and in contact with the form and inking-table, during both movements of the cylinder, an inking-table, means for applying and spreading ink on the inking-table, and means for rotating the distributing-rollers during the reciprocation of the carriage and reversing the direction of their rotation to correspond to the movement of the carriage and the impression cylinder, substantially as specified.
3. In an inking apparatus for printing presses, a carriage having form-rollers mounted in suitable bearings therein, slides to which the carriage is fastened, guides connected with the frame of the press on which the slides are supported; a reciprocating form-bed, an inking-table, a reciprocating and oscillating impression-cylinder connected with the carriage so that the form-rolls are moved over and in contact with the form and inking-table during both movements of the cylinder and the form-bed, means for applying and spreading ink on the inking-table, and means for moving the vibrating distributing-rollers endwise as the carriage is reciprocated, substantially as specified.
4. In an inking apparatus for printing presses, a carriage having form-rollers and distributing rollers mounted therein, slides to which the carriage is fastened, guides connected with the frame of the press on which the slides are supported, a reciprocating form-bed, an inking-table, a reciprocating and oscillating impression-cylinder connected with the carriage so that the form-rollers are moved over and in contact with the form and inking-table when the cylinder and carriage are moved in either direction, means for applying and spreading ink on the inking-table, and means for moving the vibrating-distributing rollers endwise as the cylinder and carriage are reciprocated, and for reversing the direction of the vibration of the distributing-rollers when the movement of the cylinder and carriage is changed at the end of their run in either direction, substantially as specified.
5. In an inking apparatus for printing presses, a carriage having a plurality of form-rollers and a plurality of distributing-rollers mounted in suitable bearings therein, slides to which the carriage is fastened, guides connected with the frame of the press on which the slides are supported, a reciprocating form-bed, an inking-table carried thereby, an oscillating and reciprocating impression cylinder connected with the carriage and by which the carriage is reciprocated and the form-rollers moved over the form and inking-table during both the forward and back movements of the cylinder and form-bed, means for applying and spreading ink on the inking-table, and means by which the distributing rollers are rotated independently of the form-rolls, substantially as specified.
6. In an inking apparatus for printing presses, a carriage having a plurality of form-rollers, and a plurality of distributing-rollers mounted in suitable bearings therein, slides to which the carriage is fastened, guides connected with the frame of the press on which the slides are supported, a reciprocating form-bed, an inking-table carried thereby, a reciprocating and oscillating impression-cylinder connected with the carriage and by which the carriage is reciprocated and the form-rolls moved over the form and the inking-table, means for applying and spreading ink on the inking-table, vibrating and rotating distributing-rollers provided with gear wheels on their ends, a rotary distributing-roller having a broad face pinion mounted on its shaft, and which is in mesh with the gear wheels on the vibrating and distributing rollers, a toothed-wheel on the cylinder and an idle-wheel mounted on a shaft supported in bearings in the carriage, whereby the oscillating motion of the cylinder is transmitted to the distributing-rollers by the idle-wheel so that they are rotated positively during the movements of the cylinder in both directions, substantially as specified.
7. In an inking apparatus for printing presses, a carriage having form-rollers and distributing-rollers mounted in suitable bearings therein, slides to which the carriage is fastened, guides connected with the frame of the press and means for adjusting the carriage vertically to adapt the form-rollers to contact with the form, substantially as specified.
8. In an inking apparatus for printing presses, a carriage having form-rollers and distributing-rollers mounted in suitable bearings therein, slides to which the carriage is fastened, guides connected with the frame of the press on which the slides are supported and set screws passed down through members of the carriage and bearing on the slides for adjusting the vertical height of the carriage and regulating the

position of the form-rolls with respect to the form, substantially as specified.

9. In an inking apparatus for printing presses, a carriage having form-rollers and distributing-rollers mounted in suitable bearings therein, slides to which the carriage is fastened, guides connected with the frame of the press on which the slides are supported, means for adjusting the form-rolls with respect to the form, and means for adjusting the distributing-rolls with respect to the form-rolls, independently thereof, substantially as specified.

10. In an inking apparatus for printing presses, a carriage having form-rollers and distributing-rollers mounted in suitable bearings therein, slides to which the carriage is fastened, guides connected with the frame of the press on which the slides are supported, means for adjusting the form-rolls with respect to the form, and means for adjusting the vibrating-rollers with respect to the form-rollers, and independently thereof, substantially as specified.

11. In an inking apparatus for printing presses, a carriage having form-rollers and distributing-rollers mounted in suitable bearings therein, slides to which the carriage is fastened, guides connected with the frame of the press on which the slides are supported, means for adjusting the form-rollers with respect to the form, and means for adjusting the distributing-rollers with respect to the form-rollers, and independently thereof.

12. In an inking apparatus for printing presses, a carriage for the form-rollers and distributing-rollers, constructed in two parts and comprising a lower part, in which the form-rollers are mounted in suitable bearings, which is fastened to slides, an upper part hinged to the lower part and having the vibrating-rollers mounted therein in suitable bearings above the form-rollers, slides to which the lower part of the carriage is fastened, and guides connected with the frame of the press on which the slides are supported, substantially as specified.

13. In an inking apparatus for printing presses, a carriage for the form-rollers and distributing-rollers constructed in two parts, and comprising a lower part, in which the form-rollers are mounted in suitable bearings, which are fastened to slides supported on guides connected with the printing press frame, and means for adjusting the said part for the purpose of regulating the contact between the form-rollers and the form, and an upper part hinged to the lower part and having the distributing-rollers mounted therein in suitable bearings, above the form-rollers, means for adjusting the upper part independently of the lower part to regulate the contact of the distributing rolls with the form-rolls, means for supplying ink to

the form-rolls, and gearing connecting the distributing-rolls with a toothed wheel on the cylinder shaft, substantially as specified.

14. In an inking apparatus for printing presses, a reciprocating carriage constructed in two parts, a lower part in which the form-rollers are mounted in suitable bearings having vertical horns, a shaft carrying an idle-wheel mounted in boxes held in frames connected with the vertical horns, slides to which the lower part of the carriage is fastened, means for adjusting the carriage vertically, means for adjusting the frames that hold the boxes in which the shaft of the idle-wheel is journaled in relation to the lower part in which the form rollers are supported, substantially as specified.

15. In an inking apparatus for printing presses, a carriage having form-rollers and distributing-rollers, constructed in two parts, a lower part in which the form-rollers are mounted in suitable bearings, having vertical horns, between which an idle-wheel shaft is mounted in boxes held in frames connected with the vertical horns, slides to which the lower part of the carriage is fastened, means for adjusting the carriage vertically and means for adjusting the frames that hold the boxes in which the shaft of the idle-wheel is journaled independently of the carriage, substantially as specified.

16. An inking apparatus for printing presses, a carriage having form-rollers and distributing rollers mounted in suitable bearings therein, the said carriage composed of a lower part which is fastened to slides and provided with means for vertically adjusting the same, vibrators mounted in the upper part of the carriage and having oppositely threaded collars on their shaft, an intermediate threaded concave block in engagement with said collars, and an oscillating and reciprocating impression cylinder geared to the distributing rolls, whereby, when the oscillating cylinder is reciprocated the carriage is moved with it and the form-rollers caused to move over the form and inking-table, the distributing rolls rotated and the vibrators moved lengthwise, as they rotate, substantially as specified.

17. In an inking apparatus for printing presses, the combination of an oscillating reciprocating impression cylinder, a reciprocating form-bed having an inking-table at its rear end, an inking apparatus consisting of a reciprocating section that carries the form and distributing-rollers and is geared to the cylinder, and a stationary section at the rear-end of the press comprising a fountain, a supply roller, a vibrating distributing roller and a doctor roller, and means for lifting the doctor-roller from the vibrator-roller to a position where the inking-table

when it moves backward with the bed passes under the ductor-roller and receives its supply of ink therefrom, substantially as specified.

5 18. In an inking apparatus for printing presses, the combination of a ductor-roller, an inking-table, a pinion, a gearing connecting the same with the driving shaft of the printing press, a vibrating distributing 10 roller mounted on a shaft and having on one end a toothed-wheel in mesh with the said pinion and on the opposite end having a worm-sleeve on it and connected with it by means of a spline, a worm-wheel in mesh 15 with said worm-sleeve, an arm coupled to the shaft and a pitman that connects the worm-wheel with the said arm, whereby, when the shaft is revolved the worm turns the worm-wheel and thereby causes the 20 worm to vibrate the distributing roller, substantially as specified.

19. In an inking mechanism for a printing press having a frame, a reciprocating form bed, and an oppositely reciprocating 25 impression cylinder arranged to move toward and from the plane of the bed, said inking mechanism comprising a carriage mounted on and supported by the frame independently of the bed and cylinder, said 30 carriage having form and distributing rollers, and connections whereby the carriage is caused positively to reciprocate with the impression cylinder without partaking of its movement toward and from the plane of the 35 form bed.

20. An inking mechanism for a printing press having a frame, a reciprocating form bed and an oppositely reciprocating impression cylinder arranged to move toward and 40 from the plane of the form bed, said inking mechanism comprising an inking table connected with the form bed, means for supplying ink to the inking table, a carriage mounted on and supported by the frame independently of the bed and cylinder, said 45 carriage having form and distributing rollers adapted to receive ink from the inking table and apply it to the form, and connections whereby the carriage is caused positively to reciprocate with the impression cylinder without partaking of its movement toward and from the form bed.

21. An inking mechanism for a printing press having a reciprocating form bed and 55 an oppositely reciprocating impression cylinder mounted in a frame arranged to move toward and from the plane of the form bed, said inking mechanism comprising a carriage mounted on and supported by the 60 frame independently of the bed and cylinder, said carriage having form and distributing rollers, guides for said carriage fixed on the frame of the machine, and connections whereby the carriage is caused positively to reciprocate with the impression cylinder.

inder without partaking of its movement toward and from the form bed.

22. An inking mechanism for a printing press having a reciprocating form bed and an oppositely reciprocating impression cylinder mounted in a frame arranged to move toward and from the plane of the form bed, 70 said inking mechanism comprising a carriage mounted on and supported by the frame independently of the bed and cylinder, said carriage having form and distributing rollers, guides for said carriage fixed on the frame of the machine between the form bed and the frame in which the impression cylinder is mounted, and connections whereby the carriage is caused positively to reciprocate with the impression cylinder without partaking of its movement toward and from the form bed. 75

23. An inking mechanism for a printing press having a reciprocating form bed and an oppositely reciprocating impression cylinder mounted in a frame arranged to move toward and from the plane of the form bed, 80 an inking table connected with the form bed, means for supplying ink to the inking table, a carriage having form and distributing rollers adapted to receive ink from the inking table and apply it to the form, guides for said carriage fixed on the frame of the machine between the form bed and the frame in which the impression cylinder is mounted, and connections whereby the carriage is caused to reciprocate with the impression cylinder without partaking of its movement toward and from the form bed. 85

24. In an inking mechanism for a printing press having a frame, a reciprocating form bed, and an oppositely reciprocating impression cylinder arranged to move toward and from the plane of the bed, said inking mechanism comprising a carriage mounted on and supported by the frame independently of the bed and cylinder, said carriage having form and distributing rollers, 100 connections whereby the carriage is caused positively to reciprocate with the impression cylinder, without partaking of its movement toward and from the plane of the form bed, and means for positively rotating the distributing rollers during the reciprocation of the carriage. 105

25. An inking mechanism for a printing press having a reciprocating form bed and an oppositely reciprocating impression cylinder mounted in a frame arranged to move toward and from the plane of the form bed, a carriage having form and distributing rollers, guides for said carriage fixed on the frame of the machine, connections whereby the carriage is caused to reciprocate with the impression cylinder without partaking of its movement toward and from the form bed, and gearing between the distributing rollers and the impression cylinder for driv- 110 115 120 125 130

ing the distributing rollers during the reciprocation of the carriage and impression cylinder.

26. An inking mechanism for a printing press having a reciprocating form bed and an oppositely reciprocating impression cylinder mounted in a frame arranged to move toward and from the plane of the form bed, a carriage having form and distributing rollers, guides for said carriage fixed on the frame of the machine, connections whereby the carriage is caused to reciprocate with the impression cylinder without partaking of its movement toward and from the form bed, gearing between the distributing rollers and the impression cylinder for driving the distributing rollers during the reciprocation of the carriage and impression cylinder, and means for vibrating the distributing rollers endwise as the carriage is reciprocated.

27. An inking mechanism for a printing press having a reciprocating form bed and an oppositely reciprocating impression cylinder mounted in a frame arranged to move toward and from the plane of the form bed, a carriage having form and distributing rollers, guides for said carriage fixed on the frame of the machine, connections

whereby the carriage is caused to reciprocate with the impression cylinder without partaking of its movement toward and from the form bed, and means for effecting an adjustment between the form rollers and the form.

28. An inking mechanism for a printing press having a reciprocating form bed and an oppositely reciprocating impression cylinder mounted in a frame arranged to move toward and from the plane of the form bed, a carriage having form and distributing rollers, guides for said carriage fixed on the frame of the machine, connections whereby the carriage is caused to reciprocate with the impression cylinder without partaking of its movement toward and from the form bed, and means for effecting a relative adjustment between the distributing rollers and the form.

In testimony that I claim the invention above set forth I have affixed my signature in presence of two witnesses.

MATTHEW VIERENGEL
